Filed Mar. 9, 1959, Ser. No. 798,105

Claims priority, application Netherlands Apr. 1, 1958
1 Claim. (Cl. 57—34)

This invention relates to the heating of synthetic thermoplastic threads or yarns and more particularly to an apparatus for heating such threads or yarns when used in conjunction with a yarn curling apparatus including a twisting device.

In U.S. Patent No. 2,869,312, having common ownership herewith, a yarn heating apparatus is described. This yarn heating apparatus may be used in conjunction with a yarn curling apparatus which includes a twisting device. Therein is described, as one embodiment, a yarn heating apparatus comprising an electrically heated, elongated tube having a longitudinal opening presenting a smooth inner surface. The diameter of this opening is not substantially greater than the diameter of the yarn to be curled. The yarn is passed through this opening in contact with substantially all portions of this inner surface and at the same time is twisted and vibrated by the twisting device. The heating tube is made of a material suitable for heating by electricity and has very thin walls.

There are certain disadvantages to the use of such thin-walled heating tubes. It has been found that the thin-walled tubes very often do not have a homogeneous resistance thereby preventing even distribution of heat over the length of the tube. Also, such tubes have a tendency to be deformed on heating, thereby necessitating mounting under strain which unduly complicates the apparatus.

A further disadvantage occurs upon the discontinuance of movement of thread through the tube. The thread remaining within the tube withdraws less heat than during normal operation. As a result, the temperature of the tube increases and may melt the thread.

Therefore it is an object of this invention to provide a heating tube not having disadvantages of known heating tubes and which is suitable for use in conjunction with a twisting device.

It is a further object of this invention to provide a heating tube that has an even distribution of heat over its inner surface.

An additional object of this invention is to provide a heating tube that does not require mounting under strain.

It is a further object of this invention to provide a heating tube that does not increase in temperature upon stoppage of thread movement to such a degree that the thread melts.

These and other objects of this invention will become apparent from a reading of the following detailed specification, in conjunction with the accompanying drawing wherein the figure is a diagrammatic view, in elevation, illustrating a continuous curling apparatus including the improved heater of this invention.

It has been found that these objects may be obtained and the disadvantages of the previously described heating tube may be overcome by utilizing a heating tube whose external diameter exceeds 2 mm., and ordinarily will not exceed 5 mm.

Such a tube, when constructed of material having suitable electrical resistance, makes possible a more uniform distribution of heat throughout the entire length of the inner surface of the tube. The tube may be constructed of any suitable resistance material, however, the preferred material is stainless steel.

It is contemplated that this tube will be used in conjunction with a thermoplastic thread or yarn curling ap-

2

paratus which includes a twisting device. The advantages of such a tube are not obtained except in conjunction with such an apparatus. This heating tube will have an inner diameter of less than 0.8 mm. and an external diameter of more than 2 mm. Stated differently, the tube wall thickness, which is one half the difference between external and internal diameters, should be at least 0.6 mm. and preferably should be greater than 75% in excess of the internal tube diameter.

Referring now to the drawing in which thermoplastic yarn 10 having, for purposes of illustration, a denier of 70 is withdrawn from supply package 11 through thread guide 12, tension device 13, and thread guide 14. From thread guide 14, the yarn passes into heater 18. Tension device 13 is a conventional tension device. Heater 18 is constructed of stainless steel and has an internal diameter of 0.5 mm. and an external diameter of 2.5 mm. It can be seen from arithmetical calculations, therefore, that the tube wall thickness, derived in the manner described above, is twice the internal tube diameter, or 100% in excess of the internal tube diameter. Heater 18 is an elongated hollow body or tube and is supported by arms 19 and 20 from a block of insulating material 21 which can be supported from a convenient part of the machine by means not shown. Electrical conduits 22 and 23 provide for an electric heating current to be applied to tube 18. The current is led to the tube from conduits 22 and 23 through arms 19 and 20.

The inner surface of tube 18 is smooth and polished. The size of the aperture in the tube is so nearly the diameter of the yarn 10 that small, low amplitude oscillations of the yarn will cause it to contact the inner wall of the tube 18 in very nearly all of its radii. Similarly, nearly all of the surface of each length of yarn is caused to contact some portion of the heating surface and the result is a considerable conservation of heat and improvement in the uniformity of heat application to the yarn being treated.

From heater 18, the yarn passes into and through a false twisting device 24 which is rotated by belt 25 and drive motor 26. The device 24 imparts a false twist to yarn 10, which twist subsequently is removed prior to take-up. The false twisted yarn passes through a cooling zone 27 and onto withdrawal godet 28, at which point substantially all of the twist is removed. Yarn leaving godet 28 is passed over guide roller 29 and collected on yarn take-up means 30.

The temporary twist imparted to yarn 10 by false twisting device 24 travels longitudinally of the yarn to such an extent that curled yarn is contained within heater 18. Device 24 causes low amplitude oscillations of yarn 10 which oscillations travel longitudinally of the yarn to such an extent that the yarn in heater 18 oscillates and contacts nearly all of the inner surface of heater 18 at some time.

The curls in the yarn 10 are set by heater 18 and remain to a large extent after removal of the false twist. If desired, thermostat 31 may be provided for controlling the amount of heat to which the yarn is subjected.

For additional details of this false twisting apparatus and control means for supplying yarn to heater 18, reference should be had to U.S. application Serial No. 513,442, filed June 6, 1955, now Patent No. 2,949,721, and having common ownership herewith.

Inasmuch as other embodiments will become apparent to those skilled in the art, it is intended that the scope of the present invention be limited only to the extent set forth in the following claim.

What is claimed is:

Apparatus for curling thermoplastic yarn comprising a twisting device for imparting curl to running lengths of yarn, an elongated metallic body constituting an electrical

resistance element having a longitudinal opening presenting a smooth inner surface through which said curled yarn is passed, the diameter of said opening being not substantially greater than the diameter of the yarn to be curled and the thickness of said elongated body between the longitudinal opening and the external surface thereof being in excess of said diameter by at least 75%, electrical means connected to said body for heating the same and thereby setting the curl imparted to said yarn by said twisting device, and means for passing thermoplastic yarn longitudinally through said opening in contact with substantially all portions of said inner surface while imparting twist and vibration thereto with said twisting device.
